ADJUSTABLE HACKSAW FRAME

Alvin L. Johnson, Worcester, Mass., assignor to Johnson Enterprises, Inc., Worcester, Mass., a corporation of Massachusetts

Filed Jan. 30, 1958, Ser. No. 712,225

4 Claims. (Cl. 145—34)

This invention relates to a new and improved adjustable hacksaw, and the principal object of the invention resides in the provision of new and useful means for imparting a tension to the hacksaw blade, said means being incorporated in a relatively simple and easily manufactured frame of novel construction whereby a mere turning of a nut or the like results in a continuous, smooth adjustment of the tension to the degree desired as contrary to the prior art addition or increase of tension by steps; and the provision of a hacksaw as above stated including means for adjustment of the frame whereby hacksaws of different lengths may be utilized in the same frame by a simple, easy and quick adjustment thereof.

Further objects of the invention include the provision of an adjustable hacksaw as above described including a frame having a handle and a telescopic end piece slidably associated with said frame, in combination with means mounted on said frame and engaging the telescopic end piece for quick and easy adjustment thereof relative to the frame for varying the tension upon a hacksaw blade member between the end-piece and the handle of the frame.

Other objects and advantages of the invention will appear hereinafter.

Reference is to be had to the accompanying drawings, in which

Fig. 1 is a view in elevation of one form of the invention;

Fig. 2 is an enlarged section on line 2—2 of Fig. 1;

Fig. 3 is a section on a reduced scale on line 3—3 of Fig. 2;

Figs. 4 and 5 are sections on the respective lines of Fig. 2;

Fig. 6 is a view in elevation of a modified form of the invention;

Fig. 7 is an enlarged section on line 7—7 of Fig. 6;

Fig. 8 is a section on a reduced scale on line 8—8 of Fig. 7; and

Figs. 9 and 10 are sections on the respective lines in Fig. 7.

In carrying out the present invention, I provide a relatively simple but comfortable hand and finger protecting handle generally indicated at 10, this handle having an opening 12 to receive the fingers of the hand. The handle also includes an integral barrel or cylinder indicated at 14, and the barrel or cylinder 14 is provided with a cylindrical tube 16 which is open at both ends and is held in position by any desired means such as welding, brazing or the like.

Within the tube 16, there is telescopingly received another slightly smaller tube 18. Tube 18 is preferably bent as at 20 to provide a relatively elongated hook or terminal portion having a pair of pins 22 upon which a hacksaw blade 24 may be secured as will be well known by those familiar with the art. The handle 10 is also pro-

2

vided with similar pins as at 26 for a like purpose and it will be clear that the hacksaw blade, which has holes at the ends thereof, may be mounted on said pins as shown in Fig. 1.

5 An elongated screw rod or the like 28 is preferably mounted within the combined tubes as is clearly shown in Figs. 2 and 3, and this elongated screw rod is meshed with a nut 30 held in fixed relation to the inner tube 18 by a set-screw or similar means 32. The screw rod 28 is rotatable by a finger piece 34 pinned or otherwise secured thereto and is held against longitudinal motion by any desired means such as adjustable set-screws 36 mounted at the rear end of the tube 16 as plainly shown in Fig. 2. These set-screws have rounded noses engaged in an annular recess 37 in rod 28.

10 It will be seen that when the screw is rotated, the nut will be traveled longitudinally, carrying with it the smaller tube 18 and this action provides for extension of the member 18, thus imparting a tension on the hacksaw blade, maintaining the same in position. The pin 38 extending through the tube 16 and into a slot 40 maintains the tube 18 against rotation.

15 In the other form of the device shown in Fig. 6, a handle 42 similar to that at 10 may be utilized, and this handle is also provided with a sleeve or ferrule 44 which, however, is slotted at 46 to accommodate a radially extending thumbnut 48.

The thumbnut 48 is secured to an elongated screw rod 50 in mesh with a nut 52 secured at 54 to an inner and 20 smaller sleeve 56, so that when the thumbnut 48 is rotated, the nut 52 and hence sleeve 56 will be advanced or retracted in order to provide tension or release the same on the hacksaw blade 58. The tube 56 is conveniently telescopingly arranged in another larger tube 60 and may be provided with a pin or the like 62 maintaining the same against rotation by being received in a slot 64 in the smaller tube 56.

25 It is to be noted that a left-hand thread is preferably used on the screw shaft 50 and for this reason the nut 52 and inner sleeve 56 are moved outwardly when the thumb and forefinger are applied to the thumbnut 48 in the usual manner.

30 It will be seen that this invention provides a very simple but effective hacksaw frame which may be extended to accommodate blades of many different lengths as indicated by the relative solid and dotted lines in Figs. 1 and 6 and at the same time by a very simple and effective means a continuously increasing tension is applied to the blades so that any degree of tautness may be 35 achieved as desired without the necessity of applying the tension by steps.

35 Having thus described my invention and the advantages thereof, I do not wish to be limited to the details herein disclosed, otherwise than as set forth in the claims, 55 but what I claim is:

1. A hacksaw comprising a handle, means on said handle mounting a tubular member in fixed relation thereto, a second tubular member telescopingly associated with the first tubular member, means on the handle and 60 the second tubular member for engaging and holding a hacksaw blade, and means associated with the first-named tubular member for extending and retracting the second-named tubular member with respect thereto, said last-named means comprising an elongated screw rod located 65 within the tubular members and engaging a nut fixed to the second-named tubular member, means to restrict longitudinal motion of the screw rod, and means to rotate the screw rod.

2. The hacksaw of claim 1 wherein said screw rod is 70 left-hand threaded.

3. The hacksaw of claim 1 wherein the nut mounted on the screw rod is supported on the handle of the hacksaw.

4. The hacksaw of claim 1 wherein the means for turning the screw rod is mounted directly thereon at the rear of the handle, said first-named tubular member extending to the rear of the handle.
